UNITED STATES PATENT OFFICE.

OSCAR BRADFORD, OF CHICAGO, ILLINOIS.

METHOD OF MANUFACTURING CONCRETE BLOCKS AND SLABS.

No. 862,440.

Specification of Letters Patent.

Patented Aug. 6, 1907.

Application filed July 20, 1906. Serial No. 326,988.

To all whom it may concern:

Be it known that I, OSCAR BRADFORD, a citizen of the United States, residing in Chicago, in the county of Cook and State of Illinois, have invented a new and useful Improvement in the Method of Manufacturing Concrete Blocks and Slabs, of which the following is a specification.

My object in this invention has been to devise a method of constructing concrete blocks and slabs adapted to be used in building construction instead of the lumber and other inferior materials commonly employed, by which the slabs and blocks may be so cheapened as to induce builders to give them the preference over other materials. I propose making these 10 slabs and blocks in large quantities and of standard sizes and dimensions so that architects can plan their buildings with special reference to the embodiment of the blocks and slabs therein. The blocks and slabs are all strengthened by embedding expanded metal or its 15 equivalent therein in such manner that they will be fitted to withstand the strains to which they will be subject in use. If kept in stock, as they may be, these blocks and slabs will be obtainable without loss of time and without waiting upon the manufacturer to prepare 20 molds for them or to cast them.

To this end, my invention consists in the process of manufacture hereinafter set forth.

In the accompanying drawing which forms a part of this specification, I show a preferred construction of 30 molding apparatus adapted to be used in the practice of my process, and in it, Figure 1 is a plan view showing the mold open and Fig. 2 is a vertical section showing the mold closed. Fig. 3 is a plan view of the upper mold.

35 I prefer to cast the slabs or blocks in two part molds, because that permits the filling of both parts simultaneously, reduces the amount of the concrete in each, and enables the positioning of the strengthening metal at the center of the slab or block after the molds have 40 been filled instead of before or during the filling, and consequently I show a two part mold in the drawing, and referring to such drawing, 4 represents the upper part or half of the mold and 5 the lower part or half thereof. The upper half is provided with a removable 45 top 6 secured in place by fastenings which will permit the removal of the top by a horizontal or sliding movement. These fastenings consist preferably of overhanging hooks 7 on the top edge of the frame of the upper mold and adapted to engage the cross bars 8 upon the cover, and thus to permit the removal of the 50 cover by a longitudinal movement and to enable the cover to resist any pressure which may come upon it from the contents of the mold. By removing the cover, the top of the block or slab being formed is exposed 55 early in the process. The lower half of the mold agrees

with the upper half in the matter of dimensions, but it is provided with a movable bottom or floor 9, having screws 10 or equivalent devices stayed in the cross frame members 11, whereby the bottom may be raised after the mold is filled, and thus cause a compression or 60 solidifying of the contents. These screws may also be used to force the block or slab out of the mold when it has become sufficiently set to allow its removal without injury. By this compression the mass of concrete in the molds is equalized to some extent if unequally distributed previously, its plastic condition permitting 65 this result.

In the use of the apparatus, both halves of the mold are filled with concrete, and a sheet of expanded metal 12 is placed upon the concrete in one of the molds, 70 preferably the upper one, and then the upper mold is inverted and its open side placed upon the open side or face of the lower mold, and the two parts of the mold are then secured together by suitable locking devices such as the link shown at 13 and the hinge 14. This putting 75 of the molds together should be done as soon as the concrete in the upper mold becomes sufficiently hardened to permit the inverting of said mold without spilling the contents. Immediately after the molds have been put together and secured, the movable bottom is forced 80 upward and solidifies all parts of the concrete at the same time and to the same extent, equalizing its density in all parts of the slab or block and forcing the concrete in the two half molds into intimate contact so that it becomes united, and filling at the same time all 85 the interstices or hollows of the reinforce metal. This should be done before what is known as the time for the initial set has expired. This compression being effected, I next remove the top of the upper mold so that the block or slab being formed is exposed to the air on 90 top, and then allow the block or slab to remain in the uncovered mold so long as may be necessary to render it firm so that it can be taken out without danger of injury to its shape or dimensions. The final removal of the slab or block may be effected by a further movement of the movable bottom which may be imparted to 95 it by the screws shown.

I prefer to employ a two part mold because that enables the filling of both at the same time, saving thereby some small portion of the initial setting time. The 100 forming of the slabs or blocks in two part molds also greatly facilitates the insertion of the reinforcing metal at the proper place in the slab or block. The apparatus is adapted to produce very smooth and perfect blocks or slabs.

105 While I have shown the two parts of the mold equal in all respects, it will be understood that one part may be of greater height than the other, and indeed this is an important feature because by varying the relative heights of the parts I am enabled to insert the reinforce 110

at any point desired. It will also be understood that the pressure is not necessarily applied from the bottom of the mold.

I claim:—

5. The improvement in the art of manufacturing concrete slabs or blocks, consisting in placing the concrete together with a reinforce sheet in the mold, the mold being adapted to support the reinforce sheet in its proper position and equalizing the concrete throughout the mold by 10 subjecting the same to uniform pressure at the same instant during the initial setting period.

2. The improvement in the art of manufacturing reinforced concrete slabs or blocks, consisting in filling two half molds with the plastic cement, then placing a metal 15 reinforce sheet upon the concrete of one-half mold, then putting the open faces of the half molds together, and retaining them in contact until the concrete has set.

3. The improvement in the art of manufacturing reinforced concrete slabs and blocks, consisting in putting the plastic material in open faced half molds, placing the open faces of the molds together with the reinforce interposed and applying pressure to the concrete so that the reinforce will be perfectly embedded and the bodies of concrete 20 thoroughly united.

4. The improvement in the art of manufacturing reinforced slabs and blocks, consisting in putting the plastic material in open faced half molds, placing the open faces of the molds together with the reinforce interposed and applying pressure to the plastic material so that the reinforce will be perfectly embedded and the bodies of plastic 25 material thoroughly united.

OSCAR BRADFORD.
